UNITED STATES PATENT OFFICE.

PEYTON L. GUEST, OF ATLANTA, GEORGIA.

VAPOR-GOVERNOR.

1,235,462.

Specification of Letters Patent. Patented July 31, 1917.

Application filed December 30, 1916. Serial No. 139,899.

To all whom it may concern:

Be it known that I, PEYTON L. GUEST, a citizen of the United States, and a resident of Atlanta, in the county of Fulton and State of Georgia, have made certain new and useful Improvements in Vapor-Governors, of which the following is a specification.

My invention is an improvement in vapor governors, and has for its object to provide mechanism for use in connection with steam heating systems, for regulating the temperature, and to prevent over pressure in the boiler and mains.

15 In the drawings:—

Figure 1 is a diagrammatic view showing a steam heating system provided with the improvement.

Fig. 2 is a top plan view of the regulating 20 column.

Fig. 3 is a vertical section,

Fig. 4 is a rear view, and

Fig. 5 is a section on the line 5—5 of Fig. 3 looking downward.

25 The present embodiment of the invention is shown in connection with the steam heating system, consisting of a furnace 1 of the usual construction, and a series of radiators 2, the furnace being connected to the radiators by a steam line 3. The condensation line 4 leads from the radiators to the improvement to be described.

This improvement comprises a column 5 having connected with the bottom thereof 35 a pipe 6, which connects with the boiler so that the water in the boiler has free access to the column. The top of the column is provided with a cover 7 having a central opening 8 and an annular series of openings 9 encircling the opening 8, said openings 8 and 9 providing free communication 40 between the interior of the column and the atmosphere.

A gage 10 is arranged at the front of the 45 column, said gage communicating with the column at the top and bottom by connections 11 and 12, and valves 13 are provided at connections 11 and 12 for shutting off the gage from the column. The connection 12 is also 50 provided with a drain valve 14.

A float 15 is arranged within the column and this float is connected in any suitable manner with the drafts of the furnace, the connection being made in part by the chain 55 16 connected with the float, and extending through the opening 8 of the cover. The ar-

rangement is such that when the float is lifted beyond the predetermined point by the expansion of the water in the boiler and in the column, the drafts will be closed. It 60 will be noticed that the float is hollow and it is of sufficient weight to keep it almost submerged.

Two auxiliary columns 17 and 18 are arranged in rear of the main column 5, and 65 the said columns 17 and 18 communicate with the main column 5 near the top of the columns by a common opening 19. Each column 17 and 18 is provided near its lower end with a threaded nipple 20 and 21, respectively, and each nipple is closed by a plug 22 and 23, respectively. Near their tops, the columns 17 and 18 have nipples 24 and 25, the latter being adapted for connection with the pipe 27 of the condensation 75 line, while the former is adapted for connection, under conditions to be presently set forth, with the pipe 26 of the condensation line, being however, normally closed by a plug 39. 80

The column 17 has a nipple 28 in its top and into this nipple is threaded one end of a pipe 26. The pipe 26 is internally threaded, and a pipe 30 is threaded into the lower end of the pipe, the said pipe 30 depending 85 into the auxiliary column 17 to near the nipple 20, and the lower end of the said pipe 30 is open.

A pipe 31 is connected with the upper end of the auxiliary column 18, the said pipe 90 being threaded into a nipple 32 at the top of the column and the said pipe 31 communicates with a condensing radiator 33, from which a pipe 34 leads, the said pipe communicating with the atmosphere in the ash pit 95 or flue or directly as the case may be.

The chain 16 passes over direction elements 35 to the ash pit door, and another chain 36 leads from the chain 16 over direction elements 37 to the damper in the flue, 100 the arrangement being such that when the float is lifted the ash pit door and the flue damper will be moved in opposite directions.

It will be noticed from an inspection of 105 Fig. 1, that the condensation line pipe which leads direct from the steam line, namely the pipe 26, opens into the short column 17, while the condensation line pipe 27 which leads from the radiators, that is from the 110 pipes 4, opens into the longer column 18. A partition 38 is arranged within the column

18, extending from the top thereof to near the bottom of the column, but being spaced apart from the bottom of the column to form a communication beneath the partition. The arrangement is such that condensation 5 from the pipe 27 must pass downwardly beneath the partition, before it can escape into the main column 5. Pressure from the condensation line pipe 26, that is pressure 10 from the steam line, must pass down through the pipe 30 to the bottom of the pipe 17 before it can pass upwardly into the column 5.

The column 18 is of greater length than the column 17, in order to preserve the 15 water seal in the column 18 when column 17 is blown out.

The nipple 24 is provided for permitting the pipe 26 to be connected at this point, where over-head conditions do not permit 20 the connection at the nipple 28, and where the pipe 26 is connected as shown, thus nipple 24 is closed by a plug 39. The plugs 22 and 23 are cleaning plugs, for permitting the columns to be cleaned.

25 The float 15 is made heavy so that it is almost submerged under all conditions in order that it may not in its upward movement at any time close the opening 19. In practice the columns 17 and 18 are filled 30 with water to near the opening 19.

In operation the governor is regulated so that zero is set even with the desired water line of the boiler, and when sufficient steam 35 pressure is generated in the boiler, the water displaced will rise in the column or cylinder 5. At the same time the water in the pipe 30, which is of brass, is displaced downward by the pressure from the steam line, and if the pressure is continued to a sufficient degree, the excess pressure will vent by way of 40 the opening 19 and the openings 8 and 9 to the atmosphere. As soon as this venting takes place, the water in the main column 5 will lower, so that there is no possibility 45 of excess pressure forcing the water from the column to overflow.

When the 9 ounce pressure mark is reached on the gage, all the water in the tube 30 will have been expelled, and if pressure 50 continues, the water in the column 17 will be lifted into the column 5. Whenever the float 15 is lifted above a predetermined point, the dampers are adjusted to shut off the draft, and the seal above mentioned, in 55 the column 17, will stand open until the boilers are looked after or until the fire burns low. At this time the condensation in the mains and radiators will refill the broken seal.

60 The action of the device is entirely automatic, depending entirely upon the pressure in the boiler, the mains and the radiators.

I claim:

1. In a steam heating system, the combination with the boiler, the radiators, the

steam line leading from the boiler to the radiators, and the condensation lines leading from the steam line and the radiators, of a governor comprising a column communicating with the atmosphere at its upper end and with the boiler at its lower end and having a gage indicating the water level of the boiler, a float in the column and connected with the drafts of the boiler to control the same, said column having auxiliary columns communicating therewith at the tops of the main and auxiliary columns, the condensation line from the radiators communicating with one of said auxiliary columns near the top thereof, the condensation line of the steam line communicating with the other of the said auxiliary columns near the top thereof, a condensing radiator communicating with the top of the first named auxiliary column, said first named auxiliary column being of less length than the last named auxiliary column and having a depending tube in the same depending to near the bottom of the said column, the last named column having a partition extending 90 to near the bottom thereof to constrain the pressure to pass beneath the partition before it can enter the main column.

2. In a steam heating system, the combination with the boiler, the radiators, the steam line leading from the boiler to the radiators, and the condensation lines leading from the steam line and the radiators, of a governor comprising a column communicating with the atmosphere at its upper end and with the boiler at its lower end, a float in the column and connected with the drafts of the boiler to control the same, said column having auxiliary columns communicating therewith at the tops of the main and auxiliary columns, the condensation line from the radiators communicating with one of said auxiliary columns near the top thereof, the condensation line of the steam line communicating with the other of the said auxiliary columns near the top thereof, a condensing radiator communicating with the top of the first named auxiliary column, said first named auxiliary column being of less length than the last named auxiliary column and having a depending tube in the same depending to near the bottom of the said column, the last named column having a partition extending to near the bottom thereof.

3. A device of the character specified comprising a column open at its upper end and adapted to communicate at its lower end with the boiler, said column having auxiliary columns communicating therewith at the top of the main and auxiliary columns, condensation lines from the steam line and the radiators, respectively, communicating with the said auxiliary columns at the tops thereof, and extending to near the bottoms

thereof, said auxiliary columns being adapted to contain a water seal, a float in the main column and adapted for connection with the drafts of the boiler to control 5 the same, the auxiliary column with which the condensation line from the radiators communicates being of greater depth than the other auxiliary column.

4. A device of the character specified, 10 comprising a column opened at its upper end and adapted for connection with the

boiler at its lower end, a float in the column and connected with the drafts of the boiler for controlling the same, the condensation lines from the steam line and the radiators, 15 respectively, communicating with the said column at the top thereof and a water seal in connection with each of the said communications, said seal in connection with the condensation line from the radiators being of greater depth than the other seal. 20
